DISPENSING PACKET OR THE LIKE

Charles E. Cloud, Wilmette, Ill., assignor to Cloud
Machine Corporation, Skokie, Ill.

Filed Dec. 3, 1971, Ser. No. 204,780

Term of patent 14 years

Int. Cl. D9—03

U.S. Cl. D9—192

FIG. 1 is a front face view, of a dispensing packet showing my new design;

FIG. 2 is a side view taken from the right side of FIG. 1;

FIG. 3 is a rear face view;

FIG. 4 is an edge view taken from the top side of FIG. 1;

FIG. 5 is an edge view taken from the bottom of FIG. 1.

The utilitarian aspects of the neck area of the shape shown are the subject of U.S. Pat. No. 3,741,384, patented June 26, 1973.

I claim:

The ornamental design for a dispensing packet or the like, substantially as shown and described.
